BUILDING PANEL

Charles Michael Dansey Peters, "Blida" Muckridge,
Youghal, County Cork, South Ireland

Filed Dec. 20, 1967, Ser. No. 9,864

Claims priority, application Great Britain July 13, 1967

Term of patent 14 years

U.S. Cl. D13—1

Int. Cl. D25—01

The back of the building panel is plain.

I claim:

The ornamental design for a building panel, substantially as shown and described.
